UNITED STATES PATENT OFFICE.

WILLIAM S. GOULINLOCK, OF WARSAW, NEW YORK.

ENSILAGE-CUTTER.

1,218,079.

Specification of Letters Patent.

Patented Mar. 6, 1917.

Application filed May 7, 1913. Serial No. 766,230.

To all whom it may concern:

Be it known that I, WILLIAM S. GOULINLOCK, a citizen of the United States, and a resident of Warsaw, in the county of Wyoming and State of New York, have invented certain new and useful Improvements in Ensilage-Cutters, of which the following is a specification.

This invention relates to an improved ensilage cutter, and more particularly to the knife wheel.

In an ensilage cutter, there is usually provided a knife wheel having a plurality of cutting blades which coöperate with a shear plate to cut fodder coming between them into small pieces, and then the pieces so cut up are fed along and deposited in a silo. In such machines, as far as I am aware, the attachment of the knives with respect to the shear plate and with respect to each other, depended almost entirely on the machining of the seat for the knife blades. This required a good deal of care and it was almost impossible to obtain exactly the same attachment for each knife blade, so that the distance of the cutting edges of the different knife blades varied with respect to the cutting edge of the shear plate. This caused an uneven and noisy running of the ensilage cutter.

It is, therefore, an object of my invention to provide a knife wheel in which the knife blades are provided with means to enable an individual adjustment of each knife blade, so as to vary the distance of its cutting edge with respect to the shear plate and with respect to the other knife blades and the body of the wheel.

To accomplish this object, each knife blade is provided with a wedge which may be adjustable to vary the distance of the blade from the body of the wheel and from the shear plate. These wedges are individually adjustable and when once located in position may be locked or secured independent of the movement or removal of the knife blades themselves, so that the knife blades can be detached for the purpose of sharpening the same without disturbing the individual adjustment therefor.

By this means, it will be seen that a great deal of machine work can be saved and besides giving a more accurate adjustment than has been possible heretofore.

In order that the pieces of cut up fodder may be fed along, the rotation of the knife

wheel is utilized to carry out this purpose. That is to say, the knife wheel, in addition to being a cutting wheel is a blower or fan, and for this purpose is provided on its rear side with fan blades located somewhat in advance of the cutting openings in the knife wheel through which the fodder, when cut, passes. It has been the custom in prior machines, to build up the body of the knife wheel from a spoked, spider wheel by plugging in between the spokes with plates which are bolted or riveted to the spider wheel, leaving just enough opening to permit the passage of the cut up material. In my invention, I have formed the body portion of the knife wheel of one solid, integral casting, leaving solely cutting openings therethrough, all portions of the body portion being formed integral with each other. By this means, I have been able to obtain a much lighter and stronger wheel, while the wheel is closed at all points except where it is desired to draw the cut up pieces of fodder through, by suction due to the fan blades secured to the wheel.

Other features and advantages together with the construction and combination of parts will be more fully set forth hereinafter and particularly pointed out in the claims.

Reference may be had to the accompanying drawings, in which like reference characters denote corresponding parts, and in which—

Figure 1 is a face view in elevation of the knife wheel, looking at it from the side on which the knife blades are located.

Fig. 2 is an enlarged section showing in detail, the connection of one of the blades of the knife wheel and its relation to the shear plate.

Fig. 3 is a view in elevation of the knife wheel, looking at it from the opposite side to that shown in Fig. 1.

Fig. 4 is a detail perspective view showing the means for reinforcing one of the fan blades and taking up the thrust thereon.

Fig. 5 is a detail sectional view showing the coöperation of the reinforcing abutment with the back leg of one of the fan blades.

Referring more particularly to the separate parts of this invention as embodied in the form shown in the drawings, 1, indicates the knife wheel which is preferably formed of one single, solid casting having cutting openings 2 provided therein. It will be noted that the cutting openings 2 are not

radially arranged, but are extended tangentially to a small circle which may be taken as the outer circumference of the hub 3 of the wheel. The wheel itself may be reinforced by having thickened portions 4, somewhat in the manner of spokes, and conveniently designated as ribs, extending along one edge of each of the openings 2, but comprising an integral part of the body portion 1 of the wheel.

Secured so as to project across each of the openings 2, there is provided a knife or cutting blade 5 which has its cutting edge extending parallel to one of the long sides 15 of the opening 2 in each case, so that this cutting edge will also have a tangential direction, and thus when the knife is rotated, will have a shear or draw cut when coöperating with a shear plate 6 to cut the fodder 20 coming therebetween.

It is essential in this type of device in order that only the cutting edge of the knife blade shall offer itself directly to the shear plate 6, that the knife blade in each instance 25 be arranged at an angle to the plane of the wheel 1. This also enables the means for attaching each knife blade to the wheel to clear the shear plate 6.

In this invention nicety of machining is 30 obviated by providing an individual adjustment for each knife blade, so that its position with respect to the knife wheel and with respect to the shear plate 6 can be individually adjusted. To accomplish this, there is 35 interposed between each knife blade and the wheel 1, a wedge 7 which is located with one edge extending parallel and adjacent to one edge of the opening 2 and with the other edge located some distance to the rear 40 thereof. The edge of the wedge 7 which extends adjacent one edge of the opening 2, is somewhat thicker than the rear edge, so that the top and bottom faces slope gradually toward each other from the front edge 45 to the rear edge. This enables the raising of the front portion of each blade higher than the rear portion, so that the cutting edge of the blade is raised above the rest 50 of the blade. The wedge 7 extends the full width of the opening 2, so that it is effective for all portions of the blade 5.

To secure the blade 5 and wedge 7 to the knife wheel 1, there is provided a plurality of bolts 8 which extend through openings 9 in the blade 5, openings 10 in the wedge 7, and openings 11 in the body portion of the wheel 1. It will be noted that the openings 11 are inclined to the plane of the wheel 1 at an angle other than 90°, so that the bolts 55 extend in line with the direction of stress. To enable the proper seating of ends 12 for the bolts 8, inclined bearing projections 13 may be provided on the backside of the body portion 1 of the wheel.

It will be noted that the openings 9 and

10 in the knife blade 5 and the wedge 7 respectively are elongated as will be seen by reference to Fig. 1, so that the knife blade as well as the wedge can be adjusted back and forth to vary the position of the knife 70 blade and the position of the wedge. That is to say, the distance of the cutting edge of the knife blade from the shear plate 6 can be varied by varying the position of the wedge 7 and by varying the position of the blade 75 itself.

It will further be noted that the two end bolts indicated specifically in Fig. 1 by the numeral 14 are located somewhat forward of the other bolts, so as to grip the ends of the 80 blade more firmly and hold it against any possible distortion.

In order that the wedge 7 in each instance may be held in any position of adjustment while admitting of the detachment of the 85 blade 5 for sharpening, the wedge 7 is provided with a pair of extensions or lugs 15 which are likewise provided with elongated slots or openings 16 through which extend bolts 17 passing also through openings 18 90 in the body 1 of the wheel. When the wedge 7 is once adjusted to any desired position, it may be held in this position of adjustment by the bolts 17 without interfering with the removal of the bolts 8 and a disengagement 95 of the blade 5 from the wheel. The lugs 15 may be flat as indicated without any bevel as they are merely required to hold the wedge in position, but the slots 16 will allow for any movement of the wedge 7 when the 100 bolts 17 are loosened, so as to adjust the position of the wedge relative to the knife wheel.

The knife blades 5 coöperate with the shear plate 6 to cut the fodder passing 105 between them into pieces of approximately one inch in length, which pieces must pass through the opening 2 to the opposite side of the fan wheel 1.

In order to bring this about and to feed 110 the cut pieces of fodder farther along to be carried into the silo, there is provided on the backside of the knife wheel 1, a series of fan blades 19 preferably one for each of the knife blades 5 and for each of 115 the openings 2. These fan blades are located preferably in advance of the openings 2, so that they will create a suction tending to draw the cut up pieces of fodder through the openings 2. The fan blades 19 are 120 shown in the form of angle plates with a securing flange 20 and a fanning flange 21. The securing flange 20 is provided with suitable openings 22 through which extend detachable bolts 23 to secure the fan blades 125 in position on the wheel 1. Corresponding openings may be provided in the wheel 1 for the bolts 23.

In order to take up any strain on the fanning flange 21, each flange is provided 130

with a reinforcing strut or rib 24 which tapers down to a toe 25 which may engage between the forks of an abutment 26 formed integral with the knife wheel 1. It will be seen that the abutment 26 forms a socket into which the strut 24 can fit and hold the fan blade 19 against any excessive strain which the bolts 23 might not be able to carry.

10 It will thus be seen that the knife blades 5 can be individually adjusted without requiring any great accuracy in the machine work and that when the adjustment is finished, all of the knife blades can be made 15 to have exactly the same relation with respect to each other and to the shear plate 6, so that the cutting wheel will have an even, uniform motion and action.

Of course, if desired, the wedges do not 20 have to be adjusted with the edges always parallel to the direction of the cutting slots 2, but may be placed askew if necessary for a desired adjustment as sufficient play in the bolt slots is provided for this purpose.

It will be further seen, by using an integral wheel with all of the space between the cutting slots or openings filled in by solid integral portions of the wheel itself, 30 that a much lighter structure can be used while obtaining the same or greater strength.

It will be further seen that by positioning the fans more or less radially just in 35 advance of the cutting opening, that the material can be drawn as cut off by the knife blades through the cutting openings in the knife wheel and forced on ahead to be disposed of in the silo.

40 While I have shown one embodiment of my invention, I do not wish to be limited to the specific details thereof, but desire to be protected in various changes, alterations and modifications which may come 45 within the scope of the appended claims.

Having thus described my invention, I claim—

1. The combination of an integral disk 50 having longitudinal slots arranged tangential to a small circle, said disk being provided with longitudinal ribs each disposed parallel to one of said slots and located in close proximity to the same, the disk being entirely closed between the slots by integral 55 solid portions of the disk itself, and knife blades secured to said disk and each extending partially over one of said slots.

2. The combination with an integral wheel 60 having slots therein arranged tangential to a small circle, knife blades extending in the same general direction as the slots and projecting across said slots, said wheel being entirely closed between said slots by integral solid portions of the wheel, an abut- 65 ment located between the outer end of each

slot and the adjacent edge of the wheel said abutment being integral with the wheel and extending the full width of the slot in order to reinforce the wheel, and a fan blade for each slot, said fan blade being secured to 70 said wheel and provided with a portion engaging the adjacent abutment.

3. The combination with a knife wheel, of a plurality of knife blades for said wheel, a wedge for each of said blades for varying the relative position of the cutting edges of said blades with respect to said wheel, and means for maintaining the adjusted positions of said wedge independent of the attachment of said blades so that said blades 80 can be moved while said wedges remain fixed.

4. The combination with a knife wheel, of a plurality of knife blades for said wheel, a wedge individual to each of said blades to 85 enable the individual adjustment of said blades to vary the position of the cutting edge of said blades with respect to said knife wheel, means for securing said blades and said wedges to said knife wheel, and means 90 independent of said first mentioned means for securing said wedges individually to said knife wheel so as to admit of the movement of said blades while said wedges remain fixed.

5. The combination with a knife wheel, of a plurality of blades for said knife wheel, a wedge interposed between each of said blades and said knife wheel, means for securing said blades and said wedges to said 100 knife wheel, each of said wedges having one or more lugs projecting therefrom beyond the range of said blades, and bolts extending through said lugs and secured to said knife wheel for securing said wedges to said knife 105 wheel independent of the means for securing said knife blades to said knife wheel.

6. The combination with a knife wheel, of knife blades on said knife wheel for drawing the cut material away from said knife blades, 110 fan blades on said knife wheel, and means for securing said fan blades to said knife wheel, each of said fan blades comprising an angle plate with a securing flange and a fanning flange, and a reinforcing rib extending rearwardly from the outer edge of 115 said fanning flange to take up the strain on said fanning blade.

7. A knife wheel comprising a disk having slots therein arranged tangentially to a 120 small circle having the central point of the disk as a center, said disk being provided with lugs integral with it and disposed adjacent the outer ends of the slots, each lug having a pocket, and fan blades attached to 125 said disk and disposed adjacent said slots, each fan blade having a toe portion extending into the pocket of the adjacent lug.

8. The combination with a wheel having slots therein, of fan blades secured to said 130

4
wheel to draw material away from said slots, and means for securing said fan blades to said wheel, each of said fan blades comprising an angle plate having a securing flange and a fanning flange, and a reinforcing rib extending rearwardly from the outer edge of said fanning flange by abutting against said wheel.

9. The combination with a knife wheel 10 having a cutting slot therein, of a knife blade projecting across said slot to cut material entering said slot, and a wedge for

adjustably displacing said knife blade with respect to said slot, said wedge bordering said slot on three sides so as to properly support the ends and intermediate portions of said knife blade with respect to said slot. 15

Signed at Warsaw, in the county of Wyoming and State of New York, this 25th day of April, 1913.

WILLIAM S. GOUINLOCK.
